US0D1108609S

(12) **United States Design Patent** (10) Patent No.: **US D1,108,609 S**
(45) Date of Patent: ** Jan. 6, 2026

(54) **COMBINED CEILING FAN MOTOR
HOUSING AND BLADE**

(71) Applicant: **Hunter Fan Company**, Memphis, TN (US)

(72) Inventors: **Patrick R. O'Connell**, Germantown, TN (US); **Claire Bernice McRoberts**, La Jolla, CA (US)

(73) Assignee: **Hunter Fan Company**, Memphis, TN (US)

(**) Term: **15 Years**

(21) Appl. No.: **29/876,093**

(22) Filed: **May 16, 2023**

Related U.S. Application Data

(60) Continuation of application No. 29/767,665, filed on Jan. 25, 2021, now Pat. No. Des. 989,941, which is a division of application No. 29/721,662, filed on Jan. 22, 2020, now Pat. No. Des. 950,883, which is a continuation of application No. 29/612,219, filed on Jul. 31, 2017, now Pat. No. Des. 876,609, which is a division of application No. 29/557,301, filed on Mar. 8, 2016, now Pat. No. Des. 801,510.

(57) **CLAIM**

The ornamental design for a combined ceiling fan motor housing and blade as shown and described.

DESCRIPTION

FIG. 1 is a top perspective view of a combined ceiling fan motor housing and blade in the environment of a ceiling fan, showing my new design;

FIG. 2 is a bottom perspective view thereof;

FIG. 3 is a top view thereof;

FIG. 4 is a bottom view thereof; and,

FIG. 5 is a side view thereof.

The broken lines illustrating portions of the combined ceiling fan motor housing and blade and the ceiling fan environment form no part of the claimed design.

1 Claim, 5 Drawing Sheets
